UNITED STATES PATENT OFFICE.

MARTIN FEYBUSCH, OF NEW YORK, N. Y., AND PAUL W. FLEISCHER, OF WEEHAWKEN, NEW JERSEY, ASSIGNEES TO NEW JERSEY MACHINE CORPORATION, OF HOBOKEN, NEW JERSEY, A CORPORATION OF NEW JERSEY.

CLUTCH-TRIPPING MECHANISM.

Application filed September 3, 1924. Serial No. 735,581.

The principal object of this invention is to provide a new and improved construction of a clutch actuating or tripping mechanism, by means of which a pair of machines, one 5 supplying material to the other for further manipulation or treatment may be caused to operate in predetermined timed relationship.

Another object is to provide a mechanism of the character described, capable of being 10 quickly and readily mounted upon or detached from either of the machines.

A further object is to provide in such a mechanism a main or primary member which may be secured to any conveniently 15 accessible rotating part of one of the machines and to provide simple and effective connections from said controlling member to a separable clutch device of the other machine, whereby said clutch will be automatically and periodically controlled by the 20 operation of the first machine.

A further object is to provide in such a mechanism, manually operable controls which 25 may be actuated to cause the timed relationship between the machines to be varied. These and further objects will appear from the following more detailed description and by reference to the accompanying drawings forming a part hereof, and wherein Fig. 1 30 is a side elevation of a pair of machines having a clutch tripping attachment constructed in accordance with the principles of our invention connected thereto, a portion only of the two machines being shown; Fig. 2 is a 35 section on the line 2-2 of Fig. 1; Fig. 3 is a detail plan view of the treadles for varying the timed relationship of the mechanism; Fig. 4 is a side elevation of the structure shown in Fig. 3 as seen from the left 40 hand side thereof and Fig. 5 is a side elevation of the structure shown in Fig. 3, as seen from the right hand side thereof.

While our invention is of general application, it is particularly adapted for controlling 45 the operation of a pair of machines such as are commonly used in the manufacture and labeling of paper boxes or containers.

In Fig. 1 of the drawings the reference 50 character A indicates a gumming machine for applying adhesive to labels, which labels after being gummed are delivered to the label affixing machine B. The gumming machine A is provided with a clutch of any well known construction but which is shown

as a one-revolution knife-clutch 10. Clutches 55 of this type are old per se and as they are well known and form no part of the present invention, a detailed description thereof is not necessary for the purposes of this application. It is necessary merely to state that 60 the pivotally mounted lever 11 is normally held, by means of a spring (not shown), within a groove provided in the clutch wheel to engage a slidable pin 12 to disconnect the clutch upon each revolution. The lever 11 65 thereof is connected by a link 13 with one end of an oscillating two armed lever 14; the other end of said lever being connected by a cable 15, and the parts to be hereinafter described with an operating part of the machine B. 70

In the example of the invention illustrated, the rotating shaft 16 of the machine B has detachably secured thereto a split cam 17, the halves of which are clamped upon said shaft by means of the bolts 18. The cam 17 is provided with the groove 19 with which the forked end 20 of the lever 21 engages. The other end of the lever 21 is provided with an apertured elongated boss 22 slidably mounted upon one end of a connecting rod 23; the other end of said rod being connected with a bell crank lever 29, to be hereinafter described. A collar 24 is suitably secured upon one end of the rod 23, adjacent to the boss 22, to serve as a stop and prevent and limit the movement of the rod 23 outwardly of the boss 22. A spring 25 coiled about the rod 23 has its ends confined between one end of the boss 22 and a collar 26 secured to said rod and serves to urge the boss 22 and lever 21 towards the right, thereby holding the forked end 20 of the lever within the groove 19 of the cam. The cam 17 is provided with a throw 27 adapted to 80 engage a pin 28 suitably secured to the lever 21 and projecting into the path of movement of the cam throw. The left hand end of the rod 23 (see Figs. 3 and 5) is pivotally secured by a pin 23^a within a fork 29^a projecting rearwardly from the bell crank 29, said bell crank being mounted for oscillation upon a vertically extending pivot pin 30, mounted within a suitable bracket 31, secured to the frame work of the machine B. The bracket 31 is provided with a pair of 90 horizontally extending bosses 32 and 33 having pivot pins 34 and 35, respectively, se- 95

cured therein. A treadle 36, which is rotatably mounted upon the pivot pin 34, is provided with a finger 37 which projects upwardly from the lever, at a point adjacent to the pivot pin 34. The upper end of the finger 37 is adapted to engage with a lug 29^a projecting downwardly from the arm 29^a of the bell crank lever, when the treadle 36 is depressed. The inner end of the foot 10 treadle 36 is formed to provide a downwardly extending finger 39 which is adapted to engage the support carrying the bracket 31 for limiting the movement of the treadle. A spring 40 has its upper end secured to a bracket 41 mounted upon the upper end of the pivot pin 30, and the lower end of said spring is secured, as at 42, to the foot treadle 36 for holding the treadle normally in its upper position.

20 Pivottally mounted upon the pivot pin 35 is a second foot treadle 42 which has at its inner end an upwardly projecting finger 43 adapted to engage with a lug 44, extending downwardly from the arm 29^b of the bell 25 crank 29. A spring 45 has one of its ends anchored, as at 46, to the bracket 31 and its other end secured, as at 47, to the treadle 42 and serves to normally hold said lever in its upper position, in which the finger 43 is out 30 of the path of movement of the lug 44. The lever 42 is provided at its rear end with a stop 48 to limit the movement of the lever caused by the spring 45.

35 A coiled spring 49 has one of its ends secured to the lower end of the pin 23^a and its other end suitably anchored as at 50 to the bracket 31 and serves to normally urge the bell crank lever 29 in a clockwise direction, and thereby normally force the rod 23 and bracket 21 towards the right (Figs. 1 and 40 3); the spring 25 and the engagement of the forked end 20 of the lever 21 with the bottom of the groove 19 serving to limit the movement of the bell crank in this direction. The outer end of the arm 29^b of the bell crank is provided with an aperture 51 with which the cable 15 is engaged, and the outer end of the arm 29^a is provided with a similar aperture 52 to permit the cable to 50 be extended to a machine located at a right angle to the location of machine A whenever such an arrangement of the machines may be necessary or desirable.

55 The operation of the device is as follows: The gumming machine A is adapted to deliver gummed labels in regularly spaced relationship to the conveyor C which carries the labels to the machine B. The machine B may be provided with any suitable transferring or feeding mechanism which receives the labels and causes them to be fixed to the containers. The particular mechanism employed for this apparatus forms no part of the present invention and therefore 60 it has not been shown in the drawing; the

machine B merely being shown in outline, as it will be understood that any desired operation may be performed by this machine, our invention not being limited to the connection of two machines of any particular character. Whatever the respective operations of the two machines may be, the cam 17 is preferably secured upon a shaft 16, of the machine B, whose rotation is an even multiple of the cycle of the operations of such machine, and the cam 17 is so positioned upon the shaft 16 that the engagement of the cam throw 27 with the pin 28 is indicative of the completion of such cycle of operations. It will be understood that the shaft 80 of the machine B which is selected for the attachment thereto of the cam 17 is geared with, or forms a part of, the driving gear of the machine B, and that its rotation is synchronous with the cycle of operations of machine B. Obviously, such shaft may normally be continuously in rotation under control of a treadle operated clutch, or under control of a one revolution clutch. The operating speeds of the two machines will 85 preferably be so proportioned that each label or other article delivered by the conveyor C from the machine A to the machine B will normally occur at the beginning of the cycle of operations of the machine B. When the cam throw 27 engages with the pin 28, the lever 21 obviously will be forced towards the left (Fig. 1), thus causing the bell crank arm 29 to be rotated in a counter-clockwise direction (Fig. 3). This rotation of the bell 100 crank will move the arm 29^b (Fig. 3) towards the right, thus exerting a pull upon the cable 15, which acting through the lever 14 and link 13 will throw the clutch lever 11 out of engagement with the pin 12 and cause 105 the machine A and conveyor C to start. If the machine A should complete its cycle before the cam throw 27 engages the pin 28 upon the next revolution of the shaft 16, the lever 11 will engage the pin 12 and stop the 110 operation of the machine A; machine A being held inoperative until the cam throw again actuates the lever 21 and connected parts. If for any reason it is desired to interrupt temporarily the feeding of the articles to the machine B, the foot treadle 42 is depressed by the operator so as to bring the finger 43 into the path of movement of the lug 44, thus preventing the movement of the bell crank by the rod 23, whereupon the 115 movement of the lever 21 caused by the cam 17 merely results in compressing the spring 25 and as long as the treadle 42 is held depressed, the reciprocating movement of the lever 21 will merely result in compressing the spring 25 and releasing it without imparting any movement to the bell crank 29. If the operator's foot is removed from the foot treadle 42, the spring 45 will throw the lever upwardly until the stop 48 thereof en- 120 125 130

gages the bracket 31, in which position, as shown in Fig. 5, the finger 43 is out of the path of movement of the lug 44 and oscillation of the bell crank is again permitted.

- 5 If the operator should desire to accelerate the feeding of the articles from the machine A to the machine B, or to cause the machine A to start its operation sooner than would be caused by the normal action of the cam 10 17, the foot treadle 36 is depressed. This causes the finger 37 to be brought into engagement with the lug 29¹ of the bell crank 29, thereby moving the bell crank in a counter-clockwise direction, pulling the cable 15 to the right and disengaging the lever 11 from the pin 12.

It will be seen that with a mechanism constructed in accordance with the principles as described above, the operation of the 20 machine A will be caused to commence in timed relationship with the machine B, and that this timed relationship may be interrupted or retarded by depressing the foot treadle 42, while the relationship may be accelerated by depressing the foot treadle 36.

While for the purpose of clarity of description and in order that the principles of the invention may be better understood, we have referred to the machine A as a gumming machine and the machine B as a label affixing machine, it will be obvious that the principles of construction are applicable to machines of any description. It will also be understood that the principles of the invention are not limited to use with a knife edge clutch of the type shown and that the movement of the parts controlled by the cam 27 could be used to cause the engagement or disengagement of any type of clutch.

40 It will be noted that the employment of a flexible connection, such as the cable 15, permits the two machines to be connected without necessitating the exact alignment of the machines in any special position and irrespective of the relative horizontal positions 45 of the clutch 10 and bell crank 29. Furthermore, the use of such a flexible connection and the split construction of the cam 17 enables the two machines to be connected quickly and easily.

We also wish it to be understood that the invention is not to be considered as limited to the specific construction and arrangement of the parts as shown in the drawings, but that various changes and modifications may be resorted to without departing from the spirit of our invention.

We claim:

1. The combination with a pair of machines, the first machine being adapted to deliver material to the second machine for further manipulation or treatment, and said first machine being provided with a separable clutch, of means to insure the operation 60 of said pair of machines in predetermined 65 70 75 80 85 90 95 100 105 110 115 120 125 130

timed relationship, said means comprising a member adapted to be detachably secured to a moving part of the second machine, a pivotally mounted lever, a resilient connection between said member and lever to cause said lever normally to be actuated by said member upon completion of the cycle of operations of said second machine, and a connection between said lever and the clutch of said first machine.

2. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated by said member upon completion of the cycle of operations of said second machine, a connection between said lever and the clutch of said first machine, and manually operable means mounted for movement into engagement with said lever to accelerate or retard the predetermined timed operative relationship between said machines.

3. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated by said member upon completion of the cycle of operations of said second machine, and a connection between said lever and the clutch of said first machine, a manually operable member mounted for movement into engagement with the said lever to prevent the normal operation of said clutch by said means.

4. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated by said member upon completion of the cycle of

- operations of said second machine, a connection between said lever and the clutch of said first machine, and a manually operable treadle mounted for movement into engagement with said lever to cause said lever to actuate said clutch irrespective of the position of said member.
5. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated by said member upon completion of the cycle of operations of said second machine, a connection between said lever and the clutch of said first machine, and a pair of manually operable treadles mounted for movement into engagement with said lever, one of said treadles, when engaged with said lever, causing the predetermined timed **operative** relationship of said machines to be accelerated and the engagement of the other of said treadles with said lever causing said relationship to be retarded.
6. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated by said member upon completion of the cycle of operations of said second machine, and a connection between said lever and the clutch of said first machine, a manually operable treadle mounted for movement into engagement with the said lever to prevent the normal operation of said clutch by said means, and resilient means connected with each of said treadles to hold them normally out of engagement with said lever.
7. The combination with a pair of machines, the first machine being adapted to deliver material to the second machine for further manipulation or treatment, and said first machine being provided with a separable clutch, of means to insure the operation of said pair of machines in predetermined timed relationship, and means comprising a member adapted to be detachably secured to a moving part of the second machine, a pivotally mounted lever, a resilient connection between said member and lever to cause said lever normally to be actuated upon the completion of the cycle of operations of said second machine and a flexible connection between said lever and the clutch of said first machine.
8. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated by said member upon completion of the cycle of operations of said second machine, and a spring to hold said treadle normally out of engagement with said lever.
9. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted lever, a resilient connection between said member and lever to cause said lever normally to be actuated upon the completion of the cycle of operations of said second machine and a flexible connection between said lever and the clutch of said first machine.
10. The combination with a pair of machines, the first machine being adapted to deliver material to the second machine for further manipulation or treatment, and said first machine being provided with a separable clutch, of means to insure the operation of said pair of machines in predetermined timed relationship, said means comprising a member adapted to be detachably secured to a moving part of the second machine, a pivotally mounted bell crank lever having a pair of arms extending substantially at right angles to each other, both of said arms being

provided with means to permit for securing thereto of a connection leading to the clutch of said first machine, and a resilient connection between said bell crank lever and said member to cause said lever to be actuated normally upon the completion of the cycle of operations of said second machine.

11. The combination with a pair of machines, the first machine being adapted to deliver material to the second machine for further manipulation or treatment, and said first machine being provided with a separable clutch, of means to insure the periodic engagement of said clutch upon the completion of a predetermined operation of said second machine, said means comprising a cam adapted to be detachably secured to a rotating shaft of the second machine, a pivotally mounted lever, a member having a portion thereof extending into the path of movement of said cam and connected to said lever, and a connection between said lever and the clutch of said first machine.

12. The combination with a pair of machines, the first machine being adapted to deliver material to the second machine for further manipulation or treatment, and said first machine being provided with a separable clutch, of means to insure the periodic engagement of said clutch upon the completion of a predetermined operation of said second machine, said means comprising a cam adapted to be detachably secured to a rotating shaft of the second machine, a pivotally mounted lever, a connecting rod having a portion of one end thereof extending into the path of movement of said cam and its other connected with said lever, said connecting rod consisting of two relatively slidable parts and a resilient connection between said parts; and a connection between said lever and the clutch of said first machine.

13. The combination with a pair of machines, the first machine being adapted to deliver material to the second machine for further manipulation or treatment, and said first machine being provided with a separa-

ble clutch, of means to insure the periodic engagement of said clutch upon the completion of a predetermined operation of said second machine, said means comprising a cam adapted to be detachably secured to a rotating shaft of the second machine, a pivotally mounted lever, a connecting rod having a portion of one end thereof extending into the path of movement of said cam and its other connected with said lever, said connecting rod consisting of two relatively slidable parts and a resilient connection between said parts; a connection between said lever and the clutch of said first machine, and a manually operatable treadle mounted for movement into engagement with said lever to prevent the movement thereof and thereby interrupt the periodic engagement of said clutch.

14. The combination with a pair of machines, the first machine being adapted to deliver material to the second machine for further manipulation or treatment, and said first machine being provided with a separable clutch, of means to insure the periodic engagement of said clutch upon the completion of a predetermined operation of said second machine, said means comprising a cam adapted to be detachably secured to a rotating shaft of the second machine, a pivotally mounted lever, a connecting rod having a portion of one end thereof extending into the path of movement of said cam and its other connected with said lever, said connecting rod consisting of two relatively slidable parts and a resilient connection between said parts; a connection between said lever and the clutch of said first machine, and a manually operatable treadle mounted for movement into engagement with said lever to move said lever and cause engagement of said clutch independently of the operation of said cam.

In testimony whereof we have hereunto set our hands.

MARTIN FEYBUSCH.
PAUL W. FLEISCHER.
